FASTENER GUIDING ATTACHMENT FOR SEWING MACHINES

William F. Van Amburg, Meadville, and Merrill D. Vincent, Conneautville, Pa., assignors to Talon, Inc., a corporation of Pennsylvania

Application September 27, 1955, Serial No. 536,808

6 Claims. (Cl. 112—136)

This invention relates to an attachment for sewing machines, and particularly to a sewing machine attachment adapted to guide elements of a slide fastener stringer disposed along a line transverse to a line of stitching by the needle of the sewing machine.

While the device or attachment of the present invention is primarily adapted for use in sewing a waistband to a pair of trousers or skirt and securing and concealing an end of the fastener stringers in place in the waistband between the edge of the waistband and the edge of the main body portion of the trousers, it may be advantageously employed in stitching a slide fastener stringer to any part of any type garment or article wherein the line of stitching is adapted to extend at right angles to the fastener stringer and pass therethrough.

The conventional slide fastener consists generally of a pair of stringer tapes having a series of spaced-apart interlocking metallic fastener elements arranged along their opposed edges. In the manufacture of a pair of trousers, at the time the waistband is adapted to be secured to the top of the trousers, the slide fastener stringers have already been attached to the leg portions and in order to attach the waistband, the slide fastener stringers necessarily have to pass through the sewing machine transverse to the line of feed, that is, transverse to the line of stitching formed by the sewing machine needle. It has been found that unless the metallic fastener elements are properly guided as they are moved to and pass the needle, the needle oftentimes strikes one of the elements, and as a result, damage to the needle or needle breakage occurs which of course is objectionable. It is to a device or attachment for guiding the fastener elements to and past the needle of the sewing machine that the present invention relates.

Accordingly, it is the general object of the present invention to provide an improved attachment for a sewing machine which is adapted to guide a slide fastener stringer together with other parts to be joined thereto to the needle of the sewing machine so that the line of stitching across the stringer will be assured to pass in a space between any two fastener elements of the stringer.

It is another object of this invention to provide a guide attachment for a sewing machine having means for guiding and folding material as it passes into the machine to the needle and including means for guiding a fastener stringer so that the line of stitching passes through the folded material and is disposed in a space between any two fastener elements and across the stringer.

It is an object of the invention to provide an improved attachment for a sewing machine by means of which a slide fastener stringer is properly guided to the needle and joined to other parts regardless on which side of the part the fastener stringer is located.

It is still another object of the invention to provide an improved attachment for a sewing machine for guiding slide fastener stringers and parts to be joined thereto to the needle which is strong and rugged and which can be

2

easily and conveniently affixed to any conventional type sewing machine.

It is also another object of the present invention to provide an improved slide fastener stringer guiding mechanism which is simple and inexpensive in its construction, and at the same time, efficient and effective in its use.

Various other objects and advantages of this invention will be more apparent in the course of the following specification, and will be particularly pointed out in the appended claims.

In the accompanying drawings, there is shown for the purpose of illustration, an embodiment which our invention may assume in practice.

In these drawings:

Fig. 1 is a fragmentary front elevational view of a pair of trousers of the type to which the present invention relates,

Fig. 2 is a sectional view taken on line 2—2 of Fig. 1,

Fig. 3 is a sectional view taken on line 3—3 of Fig. 1,

Fig. 4 is a perspective view of the improved attachment or device in accordance with the present invention,

Fig. 5 is a sectional view taken on line 5—5 of Fig. 4,

Fig. 6 is a sectional view taken on line 6—6 of Fig. 5, showing the upper finger-like member guiding the stringer positioned on the top side of the trouser material to the needle,

Fig. 7 is a view similar to Fig. 5, showing the lower finger-like member guiding the stringer positioned on the under side of the trouser material to the needle, and

Fig. 8 is an exploded perspective view showing the resilient guide plates and the finger-like members carried thereby.

For the purpose of illustration, there is shown in Figs. 1 through 3 of the drawings, a fragmentary view of the fly closure of a pair of conventional trousers. In such trouser construction, it is customary to provide a right fly or flap 2 which is secured to the right leg piece and a left fly or facing 3 which is part of the left leg piece. The left fly or facing 3 overlaps and completely conceals the right fly or flap 2 when the trousers are closed. At the open end of the fly pieces, there is provided the customary waistband 4, the free ends of which, are attached in any conventional manner such as by a button and buttonhole as shown, or by a so-called "tailor's hook" arrangement.

There is provided a conventional type of slide fastener for closing the fly. Such a fastener consists generally of a pair of stringer tapes 5 and 6 having a series of spaced-apart interlocking fastener elements 7 and 8, respectively, arranged along their opposed edges. There is also provided a conventional slider 9 for longitudinal movement along the fastener elements for engaging and disengaging the same in a well known manner.

It is the customary practice to first sew one of the tape stringers 5 to the outer side of the right fly 2 by means of a line of stitching 10 and to attach the other stringer tape 6 to the inner side of the left fly 3 by means of the stitching 12. After the stringer tapes have been sewn to their respective fly pieces, the waistband 4 is then attached thereto by means of the stitching 13.

It is the conventional practice to bury the upper ends of the stringer tapes together with a series of fastener elements arranged on the ends thereof in the waistband so as to provide a neat appearance and also a longer closure, in that, the slider can be moved to a fully closed position directly next to the waistband. Also, such a construction eliminates the need for any top stops on the upper ends of the stringers as the waistband acts to limit the movement of the slider in its uppermost position. Thus, when the waistband is attached to the upper end of the leg and fly pieces the stitches 13 will necessarily pass through the upper ends of both the stringer

tapes 5 and 6 at a spaced distance from the extreme upper ends of the tapes and in the vicinity of the fastener elements 7a and 8a arranged along the upper edges of the stringers. Usually the fastener elements 7 and 8 are of metal and when the waistband is attached to the fly pieces in the vicinity of the stringer tapes, the needle of the sewing machine oftentimes strikes the metallic scoops and consequently needle breakage occurs. Obviously, it would be desirable if the needle would be disposed in a space between any two fastener elements positioned at the top of the fastener stringers so that the line of stitching would pass through such space. Naturally, to assure that the needle would pass through such space, it would be necessary to be assured that the fastener stringer is in the correct position so that a space between any two particular fastener elements is positioned directly opposite the needle and it is to a device for guiding the stringer tapes to the needle to obtain such a result that the present invention relates, which device will be presently described.

The sewing machine attachment in accordance with the present invention as shown in Figs. 4 through 8 of the drawings, consists preferably of a bracket member 20 which is attached to the bed of a conventional type sewing machine (not shown). There is mounted on the bracket 20, a plate 21 having a guide 22 arranged to one side thereof. This guide 22 is adapted to receive the waistband material and to fold it upon itself as is the conventional practice especially in the work trouser field. This guide means terminates in a pair of spaced-apart edge folding portions 23 and 24 to one side thereof which are arranged immediately forwardly of the needle. It is the purpose of these edge folders to fold the edge of the material upon itself to conceal the raw edges so as to provide a more finished appearing garment.

There is provided another plate-like member 21a which is also attached to the bracket 20. The inner edge of the plate-like member 21a extends between the edge folder portions 23 and 24 and there is carried thereby a pair of spaced-apart, resilient, plate-like members 25 and 26 which are arranged at an acute angle relative to one another and are held in spaced relation preferably by means of a wedged-shaped block 27. It will be seen that the lower ends of both of these plate-like members 25 and 26 extend beyond the inner ends of the edge folders 23 and 24, as more clearly shown in Figs. 4 and 6. On the inner side of each of the resilient plate-like members 25 and 26, there is arranged finger-like members 28 and 29, respectively, which preferably are pointed at the extreme end thereof, as more clearly shown in Figs. 6 and 8 of the drawings. Also, it follows that the extreme inner ends of these members extend beyond the inner ends of the plate-like members 25 and 26. It will be seen that these finger-like members are arranged angularly relative to the face plate of the sewing machine and to fly pieces as they pass through the machine. The extreme ends of these finger-like members 28 and 29 are adapted to be positioned directly opposite and in alignment with the needle N of the sewing machine for a purpose hereinafter to be described. Thus, it will be seen that there is provided a pair of spaced-apart edge folders with a resilient finger-like member arranged in spaced-apart relation directly opposite one another adjacent each edge folder.

In using the attachment of the present invention, it will be understood that the trouser parts namely, the right and left leg pieces together with the fastener stringers 5 and 6, which have been previously attached to the respective sides, by means of the lines of stitching 10 and 12, respectively, are fed into the machine between the edge folders 23 and 24 and the respective plate-like members 25 and 26 with the fastener stringers together with the fastener elements carried thereby disposed in a plane transversely to the line of stitching

adapted to pass therethrough. In making up the trouser leg portions, it will be seen that one of the stringers is positioned on one face of the material of the trousers on the right fly and that the other stringer is positioned 5 on the opposite face of the material on the left fly. Thus, it will be seen that when the trouser leg portions together with the fastener stringers attached thereto, pass between the edge folders to the needle, one of the fastener stringers is positioned on the upper side of the material and the other stringer is positioned on the lower side thereof. This is the reason it is necessary to provide 10 two finger-like guide members instead of one. That is to say, the upper guide finger 28 guides the fastener stringer 5 positioned on the top side of the material and the other or lower finger-like member 29 guides the stringer 6 on the lower side of the material.

As the material together with the fastener stringers attached thereto pass between the folders 23 and 24, the finger-like member 28 or 29 as the case may be, 15 enters a space between any two fastener elements adjacent the top of the stringer thereby tending to move the fastener stringer to the right or to the left so as to align the space with the needle N. As the stringer together with the material continues to pass into and 20 through the machine, it will be seen that the resulting line of stitching is substantially in alignment with this particular space thereby eliminating any danger of the needle striking any one of the fastener elements adjacent thereto. It is important that the finger-like members 25 28 and 29 or the plates 25 and 26 to which they are attached, or both, be resilient and yieldable in order that the finger-like members contact firmly the fastener stringers and the material as they pass to the needle in 25 order to compensate for variations in thickness of fastener stringers and the material to which they are attached.

As a result of our invention, it will be seen that there is provided a simple and inexpensive attachment for guiding a slide fastener stringer in its transverse movement into and through a sewing machine which can be 30 quickly and conveniently attached to the bed of a conventional sewing machine forwardly of the needle thereof. It will be seen that our improved attachment not only guides the fastener stringer but also folds the material of the waistband upon itself together with the edges 35 thereof and presents the folded material to the needle 40 45 whereby the waistband is sewn to the body portion of the trousers in an efficient and effective manner. It will be noted that all of the guiding mechanism is stationary and free of moving parts thereby assuring that the finger-like members which are always in alignment with the needle will guide the fastener stringer accurately relative thereto.

While we have shown and described an embodiment which our invention may assume in practice, it will be 45 understood that this embodiment is merely for the purpose of illustration and description, and that other forms may be devised within the scope of our invention as defined in the appended claims.

What we claim as our invention is:

1. In an attachment for a sewing machine for guiding slide fastener stringers of the type having a series of spaced-apart interlocking fastener elements arranged along one edge thereof and disposed in a plane transversely to a line of stitching by the sewing machine needle and movement of garment parts adapted to be sewed into and through the machine which are adapted to be sewed to the fastener stringer, a pair of resilient spaced-apart plate-like members adapted to be arranged forwardly of said needle, a finger-like member carried by each of said plate-like members in opposed relation on the inner side thereof and extending beyond the inner edge thereof, said finger-like members adapted to be positioned directly opposite and in alignment with said needle and extend to a point adjacent thereto, a pair of spaced-apart edge folders adapted to be positioned forwardly

of the needle directly next to said plate-like members and to either side thereof to form folds in the garment material as the garment parts and stringer are fed at the end of said finger-like members in superimposed relation to the needle whereby the garment parts and stringer are sewn together, said stringer adapted to pass between said folders and either one or the other of said finger-like members adapted to be disposed in a space between any two fastener elements as the stringer is fed to the needle so that the needle is directly opposite said space whereby the line of stitching is assured to be located substantially in alignment with said space.

2. In an attachment for a sewing machine for guiding slide fastener stringers of the type having a series of spaced-apart interlocking fastener elements arranged along one edge thereof and disposed in a plane transversely to a line of stitching by the sewing machine needle and movement of garment parts adapted to be sewed into and through the machine which are adapted to be sewed to the fastener stringer, a pair of spaced-apart edge folders adapted to be positioned forwardly of the needle to form folds in the garment material as the garment parts are fed together with the stringer to said needle, a fastener guiding device comprising a finger-like member resiliently mounted between said edge folders which finger-like member is adapted to be positioned directly opposite and in alignment with said needle and extend to a point adjacent thereto, said edge folders adapted to cooperate with said finger-like member to position the garment parts and fastener stringer in superimposed relation at a point adjacent the end of said finger-like member as the garment parts and stringer are fed to the needle, said stringer adapted to pass between said folders and said finger-like member adapted to be disposed in a space between any two of the fastener elements as the stringer is fed to the needle so that the needle is directly opposite said space whereby the line of stitching is assured to be located substantially in alignment with said space.

3. In an attachment for a sewing machine for guiding slide fastener stringers of the type having a series of spaced-apart interlocking fastener elements arranged along one edge thereof and disposed in a plane transversely to a line of stitching by the sewing machine needle and movement of garment parts adapted to be sewed into and through the machine which are adapted to be sewed to the fastener stringer, a bracket member adapted to be attached to the machine, a pair of spaced-apart plate-like members carried by said bracket member and arranged forwardly of the needle, a finger-like member carried by each of said plate-like members in opposed relation on the inner side thereof and extending beyond the inner edge thereof, said finger-like members adapted to be positioned directly opposite and in alignment with said needle and extend to a point adjacent thereto, a pair of edge folders carried by said bracket member with one positioned above and the other below each of the plate-like members and said finger-like members whereby the same are positioned therebetween, said edge folders adapted to extend to a point adjacent the needle whereby said edge folders are adapted to position the garment parts and the fastener stringer in superimposed relation as the garment parts and stringer are fed to the needle adjacent the end of the finger-like members, said stringer adapted to pass between said folders and either one or the other of said finger-like members adapted to be disposed in a space between any two fastener elements as the stringer is fed to the needle so that the needle is directly opposite said space whereby the line of stitching is assured to be located substantially in alignment with said space.

4. In an attachment for a sewing machine for guiding slide fastener stringers of the type having a series of

spaced-apart interlocking fastener elements arranged along one edge thereof and disposed in a plane transversely to a line of stitching by the sewing machine needle and movement of garment parts adapted to be sewed into and through the machine which are adapted to be sewed to the fastener stringer, a pair of spaced-apart edge folders adapted to be arranged forwardly of the needle of the machine to form folds in the garment material as the garment parts are fed together with the stringer to the needle, a pair of spaced-apart finger-like members arranged between said edge folders which finger-like members are adapted to be positioned directly opposite one another and directly opposite and in alignment with said needle, said stringer adapted to be fed to the needle between said finger-like members and said edge folders whereby the garment parts and stringer are disposed in superimposed relation adjacent the end of said finger-like members as the garment parts and fastener stringer are fed to the needle, said stringer adapted to pass between said folders and either one or the other of said finger-like members adapted to be disposed in a space between any two fastener elements as the stringer is fed to the needle so that the needle is directly opposite said space whereby the line of stitching is assured to be located substantially in alignment with said space.

5. In an attachment for a sewing machine for guiding slide fastener stringers of the type having a series of spaced-apart interlocking fastener elements arranged along one edge thereof and disposed in a plane transversely to a line of stitching by the sewing machine needle and movement of garment parts adapted to be sewn into and through the machine which are adapted to be sewn to the fastener stringer, an edge folder having an extending portion which is substantially U-shape in cross section so as to provide a pair of spaced-apart edge folding portions adapted to be positioned forwardly of the needle and extend to a point adjacent thereto, a pair of resilient spaced-apart plate-like members arranged forwardly of said needle between said folding portions, a finger-like member carried by each of said plate-like members in opposed relation on the inner side thereof and extending beyond the inner edge thereof, said finger-like members adapted to be positioned directly opposite and in alignment with said needle and extend to a point adjacent thereto, said fastener stringer adapted to pass between said folding portions and either one or other of said finger-like members adapted to be disposed in a space between any two fastener elements as the stringer is fed to the needle so that the needle is directly opposite said space whereby the line of stitching is assured to be located in alignment with said space.

6. In an attachment for a sewing machine for guiding slide fastener stringers of the type having a series of spaced-apart interlocking fastener elements arranged along one edge thereof and disposed in a plane transversely to a line of stitching by the sewing machine needle and movement of garment parts adapted to be sewn into and through the machine which are adapted to be sewn to the fastener stringer, an edge folder having an extending portion which is substantially U-shape in cross section so as to provide a pair of spaced-apart edge folding portions adapted to be positioned forwardly of the needle and extend to a point adjacent thereto so as to form folds in the garment material as the garment parts are fed into and through the edge folder together with the fastener stringer to said needle, a fastener guiding device comprising a pair of finger-like members resiliently mounted between the folding portions of said edge folder which finger-like members are adapted to be positioned directly opposite and in alignment with said needle and extend to a point adjacent thereto and disposed to either side of the fastener stringer, said folding portions adapted to cooperate with said finger-like members to position the garment parts and fastener stringer in superimposed relation

at a point adjacent the end of said finger-like member as the garment parts and stringer are fed to the needle, said fastener stringer adapted to pass between said folding portions and said finger-like members adapted to be disposed in a space between any two of the fastener elements 5 as the stringer is fed to the needle so that the needle is directly opposite said space whereby the line of stitching is assured to be located in alignment with said space.
